(No Model.)

H. B. STRAUT

CALF WEANER.

No. 317,881.

Patented May 12, 1885.

UNITED STATES PATENT OFFICE.

HOOPER B. STRAUT, OF CULBERTSON, NEBRASKA.

CALF-WEANER.

SPECIFICATION forming part of Letters Patent No. 317,881, dated May 12, 1885.

Application filed February 12, 1885. (No model.)

To all whom it may concern:

Be it known that I, HOOPER B. STRAUT, a citizen of the United States of America, residing at Culbertson, in the county of Hitchcock and State of Nebraska, have invented certain new and useful Improvements in Calf-Weaners; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to certain new and useful improvements in calf-weaners, the same being designed more especially as an improvement upon the device described in my Patent No. 297,870, said patent being dated April 20, 1884, my present invention consisting in certain improvements, as will be hereinafter fully set forth.

In the accompanying drawings, Figure 1 is a front view showing the same applied to the nose of an animal. Fig. 2 is a perspective view. Fig. 3 is a sectional view.

A represents a metallic plate, which is provided with teeth b, which are formed integral therewith, said teeth being formed of a part 30 of the plate, which is bent at right angles with the main body portion. The upper edge of the plate A is bent upon itself, as shown at c, so as to provide a loop for the securing-pin C, the upset portion of the metal being secured 35 to the main portion of the plate by rivets d. The lower end of the plate A is also upset or

turned upon itself, so as to embrace a stiffening-wire, d'. The pointed rod C has a portion, C', bent upon itself, as shown, and said bent portion is adapted to enter an opening, 40 D, which is formed near the end of the plate A, between the two portions of the sheet of metal. This rod, after being inserted through the cartilage of the animal's nose, is forced into the space between the pieces of the plate 45 A, and this corner is upset upon the curved portion C' of the rod, so as to prevent the same being displaced.

I find this to be a much more convenient means of securing the parts to each other than 50 that shown in my prior patent, as it is difficult to bend the parts into a position and unbend them when it is desired to remove the plate after the calf has been weaned.

Having thus described an improvement up- 55 on the device described in my Patent No. 297,870, dated April 29, 1884, what I claim is—

A calf-weaner consisting of a plate having integral teeth, as described, and loop portions 60 at its upper edge, one of said loop portions being so bent as to form a pocket, D, and the pointed securing-rod having a bend, C', substantially as shown, and for the purpose set forth.

In testimony whereof I affix my signature in presence of two witnesses.

HOOPER B. STRAUT.
